UNITED STATES PATENT OFFICE.

HENRY HARRISON SUPLEE, OF NEW YORK, N. Y.

INTERNAL-COMBUSTION ENGINE.

1,237,576.

Specification of Letters Patent. Patented Aug. 21, 1917.

Application filed April 28, 1914. Serial No. 834,878.

To all whom it may concern:

Be it known that I, HENRY HARRISON SUPLEE, a citizen of the United States, residing in the State of New York, and in the 5 city and county of New York, have invented certain new and useful Improvements in Internal-Combustion Engines, of which the following is a clear and exact specification.

My invention relates to that class of 10 internal-combustion engines in which the fuel is injected into the cylinder in a liquid form, without previous vaporization by heat or carburization of air, the fuel being ignited by the heat generated by the compression of 15 air during a previous compression stroke.

My invention includes both a novel and improved engine and a method of operation for said engine.

In such engines, operating on the well-known four-cycle arrangement, a charge of 20 air is drawn in, compressed, receives the fuel during the power stroke, and the combustion product is discharged during an exhaust stroke. By suitably proportioning the ratio 25 of compression space to cylinder volume, the heat generated during the compression produces a temperature sufficiently high to ignite the charge of liquid fuel, while the high degree of compression aids in effecting a 30 complete combustion of the fuel, and enables a high thermal efficiency to be attained.

In my invention a cylinder operating as described above is used, not as the principal element in the machine for generating 35 power, but as an ignition device and combustion chamber for use in connection with a separate expansion cylinder, in which the products of combustion are delivered and allowed to expand behind a moving piston.

40 My invention is especially designed to permit engines operating under high compression pressures to be made of sufficiently small size and light weight to be suitable for use in automobiles and similar vehicles. I 45 attain this result by limiting the higher compression pressure to a cylinder of quite small bore, thus enabling this portion of the machine to be given the necessary strength without requiring excessive thickness or 50 weight. In supplying fuel to this high compression cylinder I supply more than sufficient to combine with the mass of air in the cylinder.

55 Ignition having taken place at the high compression pressure and the gases being partially expanded to a lower pressure in this small cylinder there is provided a vol-

ume of heated gases and unconsumed fuel, still possessing considerable pressure and capable of generating a proportionable 60 amount of power in a second cylinder of larger bore and volume. The lower pressure in this larger cylinder, and especially the fact that it is not required to sustain the sudden and large stresses accompanying the 65 ignition and primary combustion of the fuel, renders it possible to make this portion of the machine of moderate thickness and weight while at the same time providing ample rigidity and strength. 70

The larger cylinder is provided, not only with communication with the smaller ignition cylinder, but also has an air inlet opening or port and an exhaust port, both of these ports being provided with valves by means of which they may be opened and closed. By reason of this arrangement the larger cylinder draws in a charge of air during its suction stroke. Upon the return stroke this air is compressed, filling, not 80 only the clearance space in the cylinder itself, but also the communicating passages leading from the ignition cylinder. The volume of this total compression space, consisting of the clearance space in the large 85 cylinder and the passageway between the large cylinder and the small ignition cylinder is so proportioned that the air contained therein will be compressed to a pressure which will be as nearly as practicable equal to the 90 terminal pressure in the ignition cylinder. This condition causes absence of shock when the exhaust valve of the ignition cylinder is opened, since the gases in the ignition cylinder meet air compressed to about the same 95 pressure, and the mixture of compressed air and gases burns and expands together. 100

This compression of air in the clearance space and communicating passages prevents any sudden drop of pressure upon the opening of the exhaust valve of the ignition cylinder and renders the entire expansive force of the products of combustion in the ignition cylinder available for power production. The power absorbed in compressing 105 the air between the two cylinders is practically all returned by its expansion, while the delivery into its mass of the entire volume of heated gases from the ignition cylinder affords opportunity for the most efficient 110 conversion of heat into work.

The excess fuel supply which was injected into the ignition cylinder and which passes unconsumed therefrom with the combustion

gases, combines with the air compressed in the larger cylinder and in the passage communicating therewith and is burned, thus adding to the power developed in the larger cylinder.

5 I do not interpose any valve between the ignition cylinder and the expansion cylinder except the exhaust valve directly at the outlet of the ignition cylinder. This arrangement causes all the connecting space between the two cylinders to be in communication at all times with the large expansion cylinder, and to be wholly cut off from the ignition cylinder except during the period when the

10 exhaust valve of the ignition cylinder is open. There are therefore two distinct compression spaces in the engine; one the small clearance space in the ignition cylinder, into which air is compressed to the ignition temperature of the fuel; and the other consisting of the clearance space in the expansion cylinder, together with the communicating passages up to the back of the exhaust valve which closes the connection to the ignition

15 cylinder.

20 By using two sets of such cylinders, placed side by side, and connected to the same crank shaft by connecting rods in the usual manner, it is possible, by placing the two cranks in an angular relation of 180 degrees with each other, to cause the two sets of pistons to have opposite movements, one pair of pistons being at the lowest point in the stroke while the other pair is at the highest point, and one pair of pistons moving downward while the other is moving upward.

25 Referring to the accompanying drawings, Figure 1 shows a side view of the engine; Fig. 2, a vertical section through one set of cylinders and Fig. 3 a plan view. A, is the small, or ignition cylinder in which operates a piston, B, this piston being of plunger form, and being an extension of the larger piston C, which operates in the larger cylinder. Both pistons are positively united together, so that they move up and down as one piece, and are connected to the crank E by the connecting rod F. The cylinders are surrounded by a space G, G, G, G, this being filled with circulating water and forming a water jacket for the purpose of maintaining the working parts at a sufficiently low temperature as to prevent overheating, in the manner well-known in the

30 construction of internal combustion engines.

35 The upper portion of the small cylinder A, is formed into a clearance space a, into which are fitted valves b and c; b, being an admission valve through which external air may be drawn through the passage d. The valve c, is an exhaust valve, and when open, places the cylinder in communication with the connecting passages H, H, leading to the large cylinder D. The valves b and c open inward, and are held to their seats

by springs e, e. The opening and closing of these valves is effected by means of levers f, f, operated by cams upon the shafts g, g. I do not confine myself to this especial arrangement of valves and levers, since it is evident that valves and connections of various kinds may be used to open and shut the admission and exhaust parts of the cylinder.

70 The cam shafts g, g, are operated from the main crank shaft I, I, by means of chains and sprocket wheels, or by trains of gearing, in such a manner that the cam shafts g, g, make one revolution for every two revolutions of the crank shaft I, I.

75 The clearance space is so proportioned to the volume displaced by the piston B, that the air drawn in during the suction stroke, is compressed to a pressure sufficiently great to create a temperature high enough to ignite the heavier liquid hydro-carbons, such as petroleum or kerosene. The liquid fuel is introduced, together with air, through a small opening i in the end of the cylinder A, this opening being opened and closed by 80 a needle valve k, operated by a bell crank l, l, and cam on the cam-shaft g. The liquid fuel is preferably contained in a suitable tank r, which is so placed that the liquid will flow by gravity to the pumps from 85 which it is fed under pressure. The liquid fuel is delivered through piping p, p, to pumps s, s, operated by eccentrics or cranks t, t, on the crank shaft g, a charge of fuel being injected at every alternate stroke 90 through the pipes u, u, into the space v, around the needle valve k.

95 A compressing air pump P, which may be driven either independently or by a crank R on the crank shaft I, delivers air under 105 pressure to an air tank or receiver O, the pump being so proportioned as to maintain a pressure in the receiver O, which shall be higher than the maximum compression pressure in the clearance space of the cylinder 110 A. The compressed air tank O is in communication with the space v, so that the space v is supplied both with liquid fuel through the pipes u, u, from the pumps s, s, and with compressed air from the tank O, 115 through the pipes n, n. When needle valve k is opened oil is, therefore, positively forced into the cylinder A by reason of the higher air pressure in space v.

120 The large cylinders D, D, are provided with air inlet valves S, S, and exhausts valves T, T, operated by cams on the cam shaft g.

Having described my invention, I claim:

125 1. In an internal combustion engine, an expansion cylinder, an ignition cylinder, a passage between the two cylinders said passage being normally closed to the ignition cylinder, a piston for each cylinder said pistons being definitely related so as to move 130

simultaneously but in opposite directions, means for supplying air to the cylinders during an out stroke of their pistons, means for supplying liquid fuel to the ignition cylinder at the beginning of and during the second out stroke of its piston and means for opening said passage at the end of said last named out stroke, the said two cylinders being so proportioned that, just as the passage between them is opened, the air pressure in the expansion cylinder shall be substantially equal to that of the gases in the ignition cylinder.

2. In an internal combustion engine, two sets of similar cylinders each set comprising an ignition cylinder and an expansion cylinder, pistons for the two cylinders of each set connected together to move as one and the pistons of the two sets connected together so as to move oppositely, a passage between each ignition cylinder and the expansion cylinder of the other set both passages being normally closed, means for supplying air to the cylinders of each set on successive out strokes, means for supplying liquid fuel to

the two ignition cylinders at the beginning of and during successive second out strokes, and means for opening the two passages at the end of said last named out strokes.

3. The method of operating internal combustion engines which comprises compressing a relatively small volume of air to a degree sufficient to ignite fuel oil, injecting more than a combining proportion of fuel oil into said compressed air, compressing a relatively much larger volume of air to a lower degree and then connecting the latter volume with said former mixture of air and burning oil when said mixture has expanded to a point where its pressure is substantially the same as the pressure of the larger volume.

In testimony whereof I have hereunto set my hand in the presence of two subscribing witnesses.

HENRY HARRISON SUPLEE.
